UNITED STATES PATENT OFFICE.

MIKE GORCZYNSKI, OF CHICAGO, ILLINOIS.

IRONING BOARD.

Application filed March 10, 1926. Serial No. 93,636.

This invention relates to ironing boards, the main object of which being the provision of a board on which ironing of circular fabrics, such as skirts, shirts, etc., may be facilitated.

Another object of the invention is the provision of a collapsible ironing board, which may be collapsed when not in use, and which may occupy very little space when not in use and which may be easily transported.

A still further object of the present invention is the provision of an ironing board of the character stated which may be very inexpensively manufactured.

With the above general objects in view and others that will appear as the nature of the invention is better understood, the same consists in the novel construction, combination and arrangement of parts herein-after more fully described, illustrated in the accompanying drawing and pointed out in the appended claim.

In the drawing forming a part of this application, and in which like designating characters refer to corresponding parts throughout the several views,

Fig. 1 is a top plan view of the invention;

Fig. 2 is a side elevational view of the invention; and

Fig. 3 is a cross-sectional view through the invention in the collapsed condition, taken on line 3—3 of Fig. 2.

The invention embodies table 10 which in an operative condition of the device is supported by legs 11 and 11', which are hinged to the underface of the table 10 by means of hinges 12. The underface of said table 10 is further provided with braces 13 and 13' which are in parallel relation to each other and are transversally disposed in respect of the table 10.

Ends of braces 13 and 13' have brackets 14 pivotally mounted thereon by means of which each leg of the table is firmly held against shifting as is clearly seen on Fig. 2. The outer ends of said brackets 14 are provided with hooks 15 to engage pins 16 carried by each leg. For further strengthening the legs and guarding against lateral shifting movement of the legs in respect of the table 10, each pair of legs 11 and 11' at each end of table 10, at the upper end thereof, is joined with brace 17 and 17', respectively.

From the hereinabove description it is

apparent that each pair of legs 11 and 11' at each end of the table 10 is adapted for angular movement on hinges 12 for the purpose of folding below the said table 10 as is indicated by dotted lines on Fig. 2. So that braces 13 and 13' may not interfere with the legs when the same remain in folded position the legs of each pair are provided with a cutaway portion forming heads 18 and 18' as clearly seen on Fig. 2. When said legs remain in the folded position herein-before stated said heads will remain disposed below table 10 and adjacent the outer faces of braces 13 and 13', while the reduced portion of each leg at its upper termination will rest upon the underside of braces 13 and 13'.

It is further observed that the space between legs 11 is greater than that between the pair of legs 11' so that the respective pairs of said legs may clear each other when in a folded position, as clearly indicated in Figs. 2 and 3, in consequence of which arrangement braces 13 and 17 are longer than the corresponding braces 13' and 17' as clearly illustrated on Fig. 1.

For the purpose of preventing legs 11 and 11' from dropping down from their folded position clamp 19 made of flexible metal or other suitable material is provided under the central portion of the table 10 and pivoted thereunder on bolt 20 on which it is adapted for arcuate movement. The position of clamp 19 when the table is in use is illustrated on Fig. 1 and when the legs 11 and 11' are folded beneath the table the said clamp is brought to a transverse relation in respect of the table so that each end of the clamp may engage and maintain the legs in the folded position as illustrated on Figs. 2 and 3.

Board 21 is disposed above the table 10 and is pivoted thereto near one of its ends by means of bolt 22 of which head 23 and nut 24 are each hidden within sockets in the board and in the table, respectively. Said bolt 22 provides a pivot point for the board 21 on which said board is adapted to make angular swinging movements on horizontal plane in respect of table 10.

Block 25, preferably secured to the underface of said board 21, remains interposed between the board and the table and supports one end of the board on said table, preventing any shifting movement thereof on vertical plane. A similar block 26 is

provided at the opposite side of bolt 22 for supporting the other longer end of the board 21 and is likewise secured to the underface of said board.

For preventing shifting of the board 21 from its normal position in respect of the table 10, the maintenance of which position is preferable when the device is in a collapsed position, wedge 27 entering slots 28 and 29, made respectively in the table 10 and in the lower end of block 26, provides locking means between said board and said table.

The portion of the board to the left of the pivot is intended to provide a place for sadiron, and therefore for the purpose of preventing the falling off of the sadiron from the board, a ledge 30 is affixed thereto.

From the drawing and hereinabove made description it will be apparent that to iron circular fabrics, such as skirts, shirts, pillow cases, etc., the board 21 is swung out to the position shown by dotted lines on Fig. 1, and when in that position, owing to the fact that the longer end of the board will remain unobstructed permitting slipping of the circular fabric thereupon, the ironing of the circular fabrics will be facilitated. So also

in ironing long fabrics, such as bed sheets and spreads the board may be swung out to the position stated and the ironed portions of the fabric may be laid on the table 10 instead of allowing the same to drop to the floor as is the practice.

While there is described herein a preferred embodiment of the present invention, it is nevertheless to be understood that minor changes may be made therein without departing from the spirit and scope of the invention as claimed.

What I claim as new is:

In combination, a table top having a slot therein, an ironing board disposed above said top and pivoted thereto to swing in a horizontal plane, a pair of spaced blocks carried by said board and engageable with the table to hold the board in predetermined spaced relation thereto, said blocks being arranged on opposite sides of the pivot, one of said blocks being formed with a slot to register with said first named slot and a wedge insertable in said slots to prevent horizontal swinging movement of the board.

In testimony whereof I affix my signature.

MIKE GORCZYNSKI.
